UNITED STATES PATENT OFFICE.

ROBERT W. MURRAY, OF CORNING, OHIO.

DESIGN FOR A PUMP-BODY.

45,307.

Specification for Design.

Patented Feb. 24, 1914.

Application filed December 5, 1913. Serial No. 804,940. Term of patent 7 years.

To all whom it may concern:

Be it known that I, ROBERT W. MURRAY, a citizen of the United States, residing at Corning, in the county of Perry and State of Ohio, have invented a new, original, and ornamental Design for Pump-Bodies, of which the following is a specification, reference being had to the accompanying drawing, forming part thereof.

The figure is a perspective view of a pump body, showing my new design.

I claim:

The ornamental design for a pump body, as shown.

ROBERT W. MURRAY.

Witnesses:

JOSEPH O. FARRELL,
C. D. LEARNED.
